United States Patent Office

Des. 202,748
Patented Nov. 2, 1965

202,748

AEROPLANE

Casimir Weiss, 1734 N. Wood St., Chicago, Ill.

Filed Sept. 30, 1964, Ser. No. 81,954

Term of patent 14 years

(Cl. D71—1)

FIG. 1

FIG. 2

FIG. 3

FIG. 4

FIGURE 1 is a top plan view of an aeroplane, showing my new design;

FIGURE 2 is a side elevational view thereof;

FIGURE 3 is a bottom plan view thereof; and

FIGURE 4 is a rear view thereof.

The propellers are shown rotated 90 degrees in FIGURES 3 and 4 and the harness straps are omitted in FIG. 4 for convenience of illustration.

I claim:

The ornamental design for an aeroplane, substantially as shown and described.
